UNITED STATES PATENT OFFICE

2,566,517

SOFT FACE HAMMER

Byron R. Dicks, Lebanon, Ind.

Application March 25, 1947, Serial No. 736,968

1 Claim. (Cl. 145—36)

1

This invention relates to a hammer for all purpose use.

The chief object of the present invention is to provide a hammer that can be constructed on a mass production basis and economically and finished to specific uses, the finishing requiring a minimum of parts and these of simple construction.

The chief feature of the present invention resides in providing a hammer body of suitable material and apertured for handle reception, said body having integral threaded extensions for attachment to thread socketed caps or heads.

Another feature of the present invention resides in providing a handle-body lock that cannot become loose as is the case with conventional handle wedges and which lock is most desirable for heavy duty hammers.

The heads, disposed at opposite ends of the body, may be alike as to material or shape or may differ. Such material may be aluminum, brass, copper, steel or lead metal, or plastic or fibre, or rubber or rubber-like material, or even wood or rawhide.

In general the head is cylindrical in shape so that it readily lends itself to production from bar stock if of wood or harder metals such as steel, brass, etc.

Other objects and features of the invention will be set forth more fully hereinafter.

The full nature of the invention will be understood from the accompanying drawings and the following description and claim:

In the drawings:

Fig. 1 is a perspective view of a hammer embodying the present invention.

Fig. 2 is a central sectional view of the same.

Fig. 3 is a top plan view thereof with the upper head removed.

In the drawings 10 indicates a conventional wooden handle that drive seats into a transversely and centrally disposed bore 11 in an elongated cylindrical body 12. The bore is flared as at 13.

The body at opposite ends includes integral threaded extensions 14 which are axially aligned. The resulting structure may be formed from cylindrical bar stock in an automatic machine, etc., thus lending itself to rapid and economical production with the loss of but that part necessary to form the extensions and the bore, the latter being formed by broaching or multiple drilling and the like.

The heads also may be expeditiously and economically formed on automatic screw machines

2

and from bar stock. Each head is herein shown as a cylindrical body 15 having centrally thereof a bore 16 internally threaded at 17, the mouth of the bore being chamfered as at 18.

The bore opens upon flat face 19 and is adapted to bear upon flat face 20 at the end of the body 12. The chamfer 18 accommodates such portion (root) of threaded extension 14 as may not be threaded. Thus the actual bearing between body and head is truly annular, as it were, thus reducing the unit shock or load to be transmitted from the head to body and vice versa and also relieving the extension 14 of the same for it thus serves chiefly as a connector because it terminates short of the inner end of threaded bore 16.

Mass production of heads and bodies thus can be effected and from desired materials for it is obvious that any body can accommodate any two different kinds of heads. Also when a head becomes worn it can be readily removed and redressed or a new head substituted as desired.

Reference will now be had more particularly to Figs. 2 and 3. Therein the body is shown provided with a bore 21 parallel to the extension axis and sufficiently offset radially therefrom. This bore is so disposed that it intersects transverse or handle bore 11. Bore 21 extends from one face 20 toward the opposite face and may extend to the same or terminate short of the latter, as illustrated in Fig. 2.

The mouth of bore 21 is counterbored as at 22. After handle 10 has been drive seated in bore 11 a nail 23 is seated in bore 21 and driven through the handle, the head 24 of the nail nesting well within the counter bore 22 so as not to project beyond the face 20. Thus facial contact between body and head is assured at all times. Obviously application of the head 15 retains the nail against loss if the same ever became somewhat loose in the handle. The nail when driven home obviously forms its own hole through the handle.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claim.

The invention claimed is:

In a hammer, a generally cylindrical body of substantially uniform diameter throughout its length and having flat faces at both ends disposed at true right angles to the axis of said body, threaded extensions integral with said body and projecting axially therefrom at each of said body ends, detachable heads for each of said extensions, each of said heads having an interiorly threaded centrally disposed socket to be engaged with the threads of said extensions in face to face contact with the respective faces of said body, said body having a transversely disposed handle receiving opening in its midportion and a longitudinally disposed bore extending from one end adjacent the other end thereof through said opening and offset laterally of said extensions, and a safety pin freely receivable in

said bore to extend through a handle received in said opening and sealed therein by said detachable heads.
